Primary Examiner — Ricky Pham(74) *Attorney, Agent, or Firm* — Lowe Hauptman & Ham, LLP(57) **CLAIM**

The ornamental design for a cabinet, as shown and described.

DESCRIPTION

FIG. 1 is a perspective view of a cabinet showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The claimed design is directed to a cabinet with three components, wherein the respective components can be crossed at different angles, being characterized in the different face-shaped characters represented on the front portion of each component.

An article subject to protection of the claimed design is used for storing things and items, etc.

Materials of the claimed design are artificial marbles and the like.
